APPARATUS FOR PICKLING METAL ARTICLES

Lafe Young and Milo N. Be Dell, Alton, Ill., assignors to Laclede Steel Company, St. Louis, Mo., a corporation of Missouri

Application January 22, 1940, Serial No. 314,948

1 Claim. (Cl. 266—7)

Our invention relates to means for pickling metal articles and while it may be employed for pickling articles of any form, it is especially adapted for use in connection with tubular articles such as pipes, rod coils or the like. Difficulty has heretofore been encountered in pickling such tubular articles, particularly when their lengths are great in proportion to their diameters. This is due to the pickling fluid remaining stagnant in the relatively small bore of such tubular article, its inertia preventing its response to any general stirring or agitation of the liquid in the pickling tank.

One object of our invention is to provide pickling means in which a tank is provided with a propeller for circulating the pickling fluid therein, said propeller being so located with respect to tubular articles acted upon that the latter will act to conduct and direct the flow of liquid insuring uniform action on both the interior and exterior surfaces of the article.

Another object of our invention is to provide means for driving a propeller mounted on an approximately horizontal shaft in a pickling tank without necessitating the formation of openings in the tank walls or shell for driving connections.

A still further object of our invention is the use of a horizontal shaft through the tank in connection with the product operated upon which will serve as a conductor for the pickling fluid.

In the accompanying drawings which illustrate some forms of apparatus made in accordance with our invention, Figure 1 is a vertical longitudinal section through one end of a pickling tank; Figure 2 is a semi-diagrammatical top view; Figure 3 is a section taken on the line 3—3 of Figure 2, the caisson cap being omitted; Figure 4 is a view similar to Figure 1, but showing a modification; Figure 5 is a similar view showing a further modification; Figure 6 is a top plan view of the parts shown in Figure 5; and Figure 7 is a sectional view of another modification.

The numeral 10 indicates a pickling tank or vat and is of relatively great length with respect to its width so as to accommodate long slender tubular articles such as pipes or rod coils. Positioned adjacent one end wall of the tank is a well or caisson 11 which may be secured in place in any suitable manner. In the drawings we have shown it attached to a motor supporting platform 12 which is secured to a filler block 13 on the wall by screws 14. Mounted in the front wall of the caisson is a bearing 15 in which is journaled a horizontal propeller shaft 16. On the forward end of the shaft 16 is a propeller 17

and on the rear end a pulley wheel 18. The latter is driven by a belt 19 from the driving wheel 20 of a motor 21 carried on platform 12. To provide means for tightening the belt, the motor is not mounted directly on the platform but on a table 22 pivoted at 23 to the platform and provided with adjusting screws 24 by means of which it may be moved on its pivot. The upper end of the caisson is preferably closed by a cap 25. To prevent the pickling bath from entering the caisson around shaft 16, the bearing 15 is provided with packing 26. In case any fluid should pass the packing, it will be thrown forward by a conical rotary deflector 27 mounted on the shaft adjacent the belt so as to protect the latter from contact with the corrosive fluid. Any such fluid will collect in the sump formed by the lower end of the caisson and may be drawn off by any suitable means, such as a suction pipe (not shown). Lubricant may be supplied to the bearing by an oil pipe 28.

In the operation of our pickling apparatus the articles to be treated, shown as pipes 29, are placed in the tank in front of and closely adjacent the propeller, as shown in Figures 2 and 3. Chain slings or their equivalent indicated at 30 may be employed to insert and remove the article from the tank. The action of the propeller forces the pickling fluid through the bores of the pipes as well as the spaces between them. Such openings thus form conduits. Such openings thus direct and conduct the flow of the fluid insuring circulation throughout the entire length of the tank to effectively treat both the inner and outer surfaces of the articles.

In Figure 4 we have shown a modification of our apparatus in which in place of the caisson 11 a casting 31 is carried by the platform 12. This casting includes a tubular upright 32 terminating in an upper gear case 33 and a lower gear case 34. Extending through the upright is a vertical drive shaft 35 carrying on its upper end a bevel gear wheel 36. The wheel 36 meshes with a second bevel gear wheel 20' on the motor shaft. On the lower end of the shaft 35 is a bevel gear wheel 37 meshing with a bevel gear wheel 38 on the propeller shaft 16. The latter shaft is enclosed in a bearing 39 having a packing 26 like the bearing 15 hereinbefore described. Gears 37 and 38 are enclosed in the gear case 34 which has a cover 40 to provide an oil chamber 41 to lubricate the gears and assist the packing in preventing the entrance of the pickling fluid.

The operation of this form of our device is the same as that of the form previously described.

The casting performs the function of protecting the power transmission from the action of the fluid and thus takes the place of the caisson.

In Figures 5 and 6 we have shown a further modification. In this form of the device one end of the tank itself is partitioned off to form a well or caisson to receive the transmission gearing. Adjacent one of the end walls the tank is provided with a bulkhead 42 having a central opening 43. This opening is covered by a plate 44 of acid resisting metal which may be held in place by any suitable means such as the adjustable struts 45. Extending through the plate is a bearing 46 for the propeller shaft. This bearing is provided with a flange 47 which is welded or otherwise tightly secured to the plate to prevent entrance of the fluid through the opening therein. The bearing 46 is carried by a bracket 48 formed integral with or secured to the platform 12. Journaled in the bracket is an upright drive shaft 49 carrying a bevel gear wheel 50 engaging with a bevel gear wheel 51 on the propeller shaft. The shaft 49 may be connected to a motor on the platform 12 by bevel gearing as described in connection with the form shown in Figure 4 or driven in any other manner.

In Figure 7 we have shown a still further mod-

ification in which the driving means extends through a wall of the tank. This construction is particularly applicable where the tank 10' is made of wood. The shaft 16 extends through a bearing block 52 mounted in the end wall of the tank and making a fluid-tight joint therewith by any suitable means, such as clamping nut 53. Escape of fluid around the shaft is prevented by a packing 54 and gland 55. The propeller shaft may be an extension of the shaft of motor 21 but is preferably formed of a separate part connected thereto by a flexible coupling 56.

Having fully described our invention, what we claim as new and desire to secure by Letters Patent of the United States is:

In a device of the class described, the combination with a pickling tank, of a caisson adjacent one end of the tank, an approximately horizontal propeller shaft extending through the wall of said caisson, a propeller on said shaft in the tank, driving means for the shaft, said means including a driving belt extending upwardly through the caisson, and a rotary deflector on the shaft adjacent the belt to protect the latter from fluid entering the caisson around the shaft.
